UNITED STATES PATENT OFFICE.

CHARLES N. WHEATON, OF WARREN, RHODE ISLAND.

DESIGN FOR A CABINET OR SIMILAR ARTICLE.

40,468.

Specification for Design.

Patented Jan. 25, 1910.

Application filed November 3, 1909. Serial No. 526,154. Term of patent 7 years.

To all whom it may concern:

Be it known that I, CHARLES N. WHEATON, a citizen of the United States, residing at Warren, in the county of Bristol and State of Rhode Island, have invented a certain new, original, and ornamental Design for a Cabinet or Similar Article, of which the following is a specification.

In the accompanying drawing which forms a part of this specification, the figure is a perspective view of a cabinet showing my design.

I claim:—

The ornamental design for a cabinet or a similar article, as shown.

CHARLES N. WHEATON.
